UNITED STATES PATENT OFFICE.

WILLIAM F. GRAVER, OF CHICAGO, ILLINOIS.

LIFTING JACK.

Application filed September 5, 1922. Serial No. 586,240.

To all whom it may concern:

Be it known that I, WILLIAM F. GRAVER, citizen of the United States, residing at Chicago, in the county of Cook and State of Illinois, have invented a certain new and useful Improvement in Lifting Jacks, of which the following is a full, clear, concise, and exact description.

My invention relates to lifting jacks and 10 has for its object the provision of supplemental means whereby the range of lifting movement thereof may be increased.

The invention resides in providing a hollow pedestal open at its top to permit the 15 rack supporting body of the jack to project upwardly therethrough and also at one side sufficiently to permit of the sidewise insertion of the lower part of the rack supporting body. This pedestal has formations 20 therein for supporting the rack supporting body at selected heights with sufficient space above each formation to receive the lateral extensions that are commonly found upon the bottoms of such rack supporting bodies.

25 In the preferred embodiment of the invention the supporting formations are in the nature of ledges located one above another. In order that there may be no lateral displacement of the jack after it is adjusted 30 upon its pedestal the ledges or other supporting formations are upwardly extended at the open side of the pedestal.

The invention will be more fully explained 35 by reference to the accompanying drawing in which Fig. 1 is a side view of a lifting jack with the preferred form of pedestal of my invention shown in section; Fig. 2 is a front view of the lifting jack with its pedestal shown partially in elevation and partially in section; Fig. 3 is a 40 sectional view on line 3—3 of Fig. 1; and Fig. 4 is a perspective view of the pedestal.

Like parts are indicated by similar characters of reference throughout the different 45 figures.

The lifting jack to which the pedestal of my invention may be adapted may vary in construction. The jack illustrated includes one of the many forms of rack supporting bodies 1 in which the load lifting rack 2 50 may be moved by means of a lever 3 operating through any suitable form of gearing such as that indicated at 4. The supporting body is laterally extended at its bottom, as indicated at 5.

55 The hollow pedestal 6 illustrated is open

at its top to permit the rack supporting body to project upwardly therethrough. It is also open at one side to permit of the sidewise insertion of the lower part of the rack supporting body. The supporting formations for the rack supporting body are desirably in the nature of ledges 7, 8 and 9 that are integrally cast or otherwise disposed upon and within the pedestal. The bottom 10 of the pedestal may also be employed to support the rack supporting body in its first stage of lifting adjustment. The ledges are upwardly projected at the open side of the pedestal, as indicated at 11, and the pedestal bottom has upward projections 12 also at the open side of the pedestal. The projections 11 or 12 serve to prevent the rack supporting body of the jack from moving laterally out of the pedestal except when the bottom of the rack supporting 75 body of the jack is lifted to be in register with the spaces above those projections and through which spaces the base of the rack supporting body is passed to the selected 80 level of lifting adjustment desired for the rack supporting body.

The top of the pedestal is desirably inwardly extended (as indicated at 13) sufficiently to enable it also to support the jack, 85 in extreme cases.

The device of my invention is of particular service in connection with lifting jacks that are employed in conjunction with automobiles, the hollow pedestal enabling the employment of a single jack in different 90 locations requiring different ranges of lifting movements of the jack.

While I have herein shown and particularly described the preferred embodiment of my invention I do not wish to be limited 95 to the precise details of construction shown as changes may readily be made without departing from the spirit of my invention, but having thus described my invention I claim as new and desire to secure by Letters 100 Patent the following:

1. The combination with a lifting jack whose rack supporting body is laterally extended at its bottom; of a hollow pedestal open at its top to permit the rack supporting body to project upwardly therethrough and also at one side sufficiently to permit of the sidewise insertion of the lower part of the rack supporting body into the interior of the pedestal, the pedestal having 105 ledges therein for supporting said body at 110

selected heights and located one above another, with sufficient space above each to receive the extended bottom of the rack supporting body, said ledges having upwardly extending projections at the open side of the pedestal to retain the rack supporting body.

2. The combination with a lifting jack whose rack supporting body is laterally extended at its bottom; of a hollow pedestal open at its top to permit the rack supporting body to project upwardly therethrough, and also at one side sufficiently to permit of the sidewise insertion of the lower part of the rack supporting body into the interior of the pedestal, the pedestal having a ledge therein with sufficient space above and below it to receive the extended bottom of the rack supporting body, said ledge being upwardly projected at the open side of the pedestal to retain the rack supporting body.

3. The combination with a lifting jack whose rack supporting body is laterally extended at its bottom; of a hollow pedestal open at its top to permit the rack supporting body to project upwardly therethrough, and also at one side sufficiently to permit of the sidewise insertion of the lower part of the rack supporting body into the interior of the pedestal, the pedestal having supporting formations therein for supporting said body at selected heights located one above another, with sufficient space above each to receive the extended bottom of the rack supporting body, said formations having upwardly extending projections at the open side of the pedestal to retain the rack supporting body.

In witness whereof, I hereunto subscribe my name this 31st day of August A. D., 1922.

WILLIAM F. GRAVER.
